INSOLE HOLDDOWN FOR LASTING MACHINES

Theodore P. Courchene, Beverly, Mass., assignor
to United Shoe Machinery Corporation, Flem-
ington, N. J., a corporation of New Jersey

Application July 16, 1951, Serial No. 236,908

13 Claims. (Cl. 12—14.2)

1
This invention relates to lasting machines, and is herein shown as applied to a machine the general organization of which is substantially as disclosed in United States Letters Patent No. 1,843,232, granted on February 2, 1932, on an application of B. Jorgensen's. It is to be understood, however, that the invention is not limited to this illustrative embodiment.

Machines such as shown in the above-mentioned Letters Patent are used for lasting tennis shoes or the like which are commonly made on metal lasts and in the lasting of which the uppers are secured to insoles on the lasts by adhesion. Such a machine includes toe-lasting mechanism, heel-lasting mechanism and opposite side-lasting mechanisms, whereby the entire shoe is lasted. The operator mounts a last bottom upward in the machine with an upper loosely positioned thereon and while controlling the loose upper with his hands presses with his knee on a plunger which causes the heel-lasting mechanism and the side-lasting mechanisms to be moved inwardly by springs into positions to clamp the upper against the heel end and sides of the last. Thereafter he positions a loose insole on the bottom of the last and starts the power operation of the machine, whereupon the last and shoe are moved downward with the heel-lasting mechanism relatively to the toe-lasting mechanism and the side-lasting mechanisms by a toe presser foot and a heel presser foot engaging the toe and heel ends of the insole respectively, as explained in detail in the above-mentioned Letters Patent. The toe presser foot is carried by an arm which, by means of a handle thereon, the operator swings forwardly about a vertical axis to position the presser foot over the toe end of the shoe, and by this swinging movement of the arm the machine is started. The operator is accustomed thus to swing the arm with his left hand and at the same time to hold the loose insole against displacement by engaging it with the thumb and one or more fingers of his right hand over the forepart of the last. It will be understood that upon the starting of the machine the toe presser foot is carried downwardly into engagement with the insole.

The present invention provides means for relieving the operator of the necessity of holding the insole as above described when he starts the machine. Among other advantages, this insures against possible injury of the operator's right hand, since to hold the insole he might accidentally so position his thumb as to be caught between the insole and the toe presser foot when the latter

2
descends. For the purpose in view, the construction shown comprises a holddown arranged to engage the insole and to press it on the bottom of the forepart of the last, and means for thus applying the holddown to the insole after the operator has properly positioned the latter on the last but prior to the starting of the machine. In order that the holddown may be moved from an initial retracted position into insole-engaging position with as little inconvenience and effort as possible on the operator's part, a member is arranged conveniently to be engaged and depressed by the operator's left arm while he is holding the insole with both his hands in proper relation to the last and by such depression to move the holddown in a predetermined path to a position over the bottom of the shoe, whereupon a spring acts automatically to move the hold-downwardly into engagement with the insole. At the proper time in the operation of the machine the holddown is retracted from the shoe, a power-operated member serving to move it vertically upward away from the shoe, whereupon the above-mentioned spring acts automatically to swing it away from over the shoe to its initial position.

The above and other features of the invention, including various novel details of construction and combination of parts, will now be more particularly described with reference to the accompanying drawings and thereafter pointed out in the claims.

In the drawings,

Fig. 1 is a view in front elevation of portions of the machine to which the invention is herein shown as applied, to the parts being shown as they appear shortly after the starting of the power operation of the machine;

Fig. 2 shows mainly in elevation the left-hand upper portion of the machine as viewed from the right with reference to Fig. 1, the parts being in the same positions as in Fig. 1;

Fig. 3 is a view in rear elevation of the toe-lasting mechanism and parts associated therewith for purposes of this invention;

Fig. 4 shows in elevation certain parts included in the machine as viewed in the opposite direction from the parts shown in Fig. 2; and

Fig. 5 is a view in the same direction as Fig. 2 of the parts provided for purposes of this invention with these parts in their initial positions.

In view of the disclosure in the above-mentioned Letters Patent, only such portions of the machine as it is necessary to refer to for an understanding of the invention will be herein

described. The last and shoe are supported bottom upward for the lasting operation by a vertically movable slide 2 (Fig. 1) mounted to move downwardly in guideways in the frame against the resistance of a spring 4 and also by a downwardly movable toe rest 5, the slide 2 being provided with a last pin 6 arranged to enter the usual spindle hole in the heel end of a metal last. For lasting the shoe the machine is provided with toe-lasting mechanism 8, heel-lasting mechanism 10 and opposite side-lasting mechanisms 12 (Figs. 1 and 4), the heel-lasting mechanism being carried by the slide 2 to move downwardly and upwardly therewith relatively to the toe-lasting mechanism and the side-lasting mechanisms. The side-lasting mechanisms (Fig. 4) include flexible straps 14 arranged to be pressed against the sides of the shoe by blocks 16 mounted on arms 18 to cause them to wipe the upper heightwise of the last in response to downward movement of the last, and also include fingers 20 which act thereafter through the straps 14 to lay the marginal portion of the upper inwardly over the insole. Associated with the side-lasting mechanisms in the machine herein shown are clamping fingers 21, which, simultaneously with the starting of the power operation of the machine, are moved inwardly to positions over the bottom of the shoe, as illustrated in Fig. 4, and at the beginning of the cycle of operations are thereafter moved downwardly and outwardly into positions to clamp the marginal portions of the upper against the straps 14 before the shoe is moved downwardly, as disclosed in a copending application of mine Serial No. 166,389, filed on June 6, 1950.

In presenting the work to the machine the operator mounts the last, with the upper loosely assembled thereon, on the last pin 6, and while holding the upper with his fingers in proper relation to the last he presses with his knee on a plunger (not shown) which corresponds to the plunger 72 shown in Letters Patent No. 1,843,232, and thereby causes the heel-lasting mechanism and the opposite side-lasting mechanisms to move inwardly toward the shoe into positions to clamp and hold the upper against the last. The operator then places a loose insole on the bottom of the last within the more or less upstanding marginal portion of the upper. Thereafter, upon the starting of the power operation of the machine, the shoe is moved downwardly with the slide 2 and the heel-lasting mechanism relatively to the toe-lasting mechanism and the side-lasting mechanisms by a heel presser foot 22 (Fig. 1) engaging the heel end of the insole and a toe presser foot 24 (Fig. 2) engaging the toe end of the insole. The toe presser foot is carried by an arm 26 mounted to swing forwardly and rearwardly about the vertical axis of a post 28 on which it is secured, this arm being provided with a handle 30 by which the operator swings it forwardly with his left hand to carry the toe presser foot into position over the toe end of the shoe. By means not herein shown in detail, but constructed as disclosed in Letters Patent No. 1,843,232, the starting of the machine is effected by this forward swinging movement of the arm 26, the starting means including a member 32 (Fig. 1) which corresponds to the member 400 shown in said Letters Patent. To insure against displacement of the loose insole relatively to the last until after the presser feet 22 and 24 have engaged the insole, it is customary for the operator to hold the insole in proper position by

engaging it with the thumb and one or more fingers of his right hand over the forepart of the last.

As a safeguard against possible injury of the operator's right hand by being caught between the toe presser foot 24 and the insole or, if the machine is provided with the clamping fingers, by being engaged by these fingers when they are operated, the present invention provides means for controlling the insole in such manner that the operator need not use his right hand for this purpose at the time when he starts the machine. This controlling means includes a holdown 34 having downwardly extending fingers 36 spaced apart widthwise of the shoe for engagement with the insole over the forepart of the last. The holdown is pivotally mounted on a stud 38 threaded in the downturned front end of a forwardly and rearwardly extending rod 40 to permit it to adjust itself to the bottom of the shoe. A spring 42 connected to the rod and the holdown holds the latter normally in a relation to the rod which is approximately that which it assumes upon engagement with the insole. The rod 40 near its rear end extends through a sleeve 44 formed integral with a block 46 which is adjustable upwardly or downwardly on the upper end of a downwardly extending bar 48 and is held in adjusted position by a clamp screw 50 extending into the bar through a slot in the block. Threaded on the rod 40 at the opposite ends of the sleeve 44 are nuts 52 by which the rod and the holdown 34 thereon may be secured in different positions of adjustment widthwise of the shoe relatively to the bar 48.

The bar 48 is supported on a bracket 54 which is secured on the rear of a slide 56 adjustable lengthwise of the shoe and supporting the toe-lasting mechanism 8, this slide corresponding to that identified as 232 in Letters Patent No. 1,843,232. The lower portion of the bar 48 is confined laterally between a vertical web 58 formed on the bracket 54 and a member 60 cooperating with the web to provide a guideway in which the bar is movable downwardly and upwardly and may also swing forwardly and rearwardly. The bar 48 is further guided and controlled by a vertical slot 62 in the web 58 through which extends a stud 64 on the lower end of the bar, and by a slot 66 in the web in which lies a roll 68 carried by the bar. As shown in Fig. 5, the slot 66 has different portions in divergent relation to each other, comprising a vertical portion parallel to the slot 62 and a rearwardly and downwardly inclined curved portion in the rear lower end of which the roll 68 lies when the bar 48 is in its initial position. A spring 70 connected to the bar and to a lug 72 on the web 58 tends to hold the bar in that position with the holdown 34 retracted rearwardly from the position which it occupies when over a shoe.

To cause the holdown 34 to be applied to the insole the bar 48 is swung forwardly about the axis of the stud 64 until the roll 68 on the bar arrives at the junction of the two different portions of the slot 66, at which time the holdown is positioned directly over the insole on the last. As soon as the roll arrives in that position the spring 10 automatically moves the bar 48 and the holdown bodily downward in a rectilinear path until the holdown engages the insole and presses it against the bottom of the last. For thus swinging the bar 48 forwardly there is rotatably mounted in a pair of upstanding lugs 74 formed on a cover plate 76 positioned over the

toe-lasting mechanism a forwardly and rearwardly extending shaft 78 having fast on its front end an arm 80 on the left-hand end of which is mounted a rubber pad 82. Fast on the rear end portion of the shaft 78 and extending therefrom in the opposite direction as compared with the arm 80 is an arm 84 connected by a downwardly extending link 86 to a short arm 88 fast on a small rockshaft 90 mounted in a lug on the member 68, the connection between the link 86 and the arm 88 including a ball joint. Also fast on this rockshaft is an upwardly and rearwardly extending arm 92 of angular shape, an end portion of which is in position to engage the rear edge of the bar 48. It will thus be seen that in response to downward pressure applied to the pad 82 the link 86 is moved upwardly to cause the arm 92 to impart forward swinging movement to the bar 48 until the roll 68 arrives at the upper end of the vertical portion of the slot 66. The pad 82 is so positioned that the operator may conveniently move it downwardly by engaging it with his left arm while he is using both hands to position and hold the insole in proper relation to the last. Not only is the operator thus relieved of the necessity of thereafter holding the insole properly positioned on the last with one hand while he swings the arm 26 forwardly with the other hand to start the machine, but the pressure applied to the insole by the hold-down 34 under the influence of the spring 70 is such as to afford better insurance that the insole will be securely held in proper position until it is engaged by the presser feet 22 and 24. When the shoe is moved downwardly by the presser feet, the hold-down 34 is moved downwardly with it by the spring 70, the slot 62 and the vertical portion of the slot 66 extending far enough downwardly to permit this.

The hold-down 34 engages the insole between the extreme end portions of wipers 94 (Fig. 2) which are parts of the toe-lasting mechanism corresponding to the wipers 298 of Letters Patent No. 1,843,232. To prevent interference with these wipers provision is afforded for returning the hold-down 34 to its initial position prior to any substantial inward movements of the wipers. Conveniently the hold-down is moved reversely upward away from the shoe through connections with mechanism included in the machine for operating the wipers. As disclosed in Letters Patent No. 1,843,232, the wipers 94 are operated by a pair of rack bars 96 each engaged by a gear sector 98 fast on a rockshaft 100 (Fig. 3), only one of the gear sectors being herein shown. For the purpose in view this gear sector engages and operates another gear sector 102 pivotally mounted on an L-shaped bracket 104 one arm of which is secured by screws 105 to the cover plate 76. Integral with the gear sector 102 is an arm 106 on which is pivotally mounted a member 108 provided with a bore through which extends a rod 110 connected at its lower end by a ball joint to the stud 64 on the lower end of the bar 48. On the upper end of the rod 110 is formed an enlarged head 112 which, as shown in Fig. 5, is positioned initially a substantial distance above the member 108. When the hold-down is applied to the insole and the shoe is thereafter moved downwardly in the manner hereinbefore described, the rod 110 is moved downwardly by the bar 48 until its head 112 is nearly in position to engage the member 108 on the arm 106, as illustrated in Fig. 3. When the wipers are operated to wipe the marginal portion of the toe end of

the upper inwardly over the insole the arm 106 is swung upwardly, causing the member 108 to raise the rod 110 and thereby to move the bar 48 and the hold-down vertically upward until the roll 68 arrives at the upper end of the vertical portion of the slot 66. When the roll arrives in this position the spring 70 automatically swings the bar 48 rearwardly to carry the hold-down away from over the shoe, the spring being so arranged relatively to the bar that it acts, when permitted, thus to swing the bar. In this manner the bar is returned to the position determined by engagement of the roll 68 with the web 58 at the lower rear end of the rearwardly inclined portion of the slot 66.

The manner in which the hold-down 34 is operated and controlled having thus been fully explained in connection with the description of the structure provided, no further description of the operation is necessary. While the hold-down, in the construction herein shown, is disclosed as for holding a loose insole in position on the last, it is to be understood that in various novel aspects the invention is not limited to a hold-down which serves this particular purpose.

Having thus described my invention, what I claim as new and desire to secure by Letters Patent of the United States is:

1. In a lasting machine, means for supporting a shoe bottom upward for a lasting operation thereon, a hold-down for engaging the bottom of the shoe, said hold-down being mounted for movement by the operator from an initial retracted position to a position over the bottom of the shoe, a spring arranged to move the hold-down automatically downwardly into engagement with the shoe upon its arrival in position over the bottom of the shoe, and means for supporting the hold-down against downward movement by said spring until it has arrived in that position and for then releasing it to the action of the spring.

2. In a lasting machine, means for supporting a shoe bottom upward for a lasting operation thereon, a hold-down for engaging the bottom of the shoe, said hold-down being mounted for movement by the operator widthwise of the shoe from an initial retracted position to a position over the bottom of the shoe, and a spring arranged to impart to the hold-down automatically rectilinear downward movement into engagement with the shoe upon its arrival in position over the bottom of the shoe.

3. In a lasting machine, means for supporting a shoe bottom upward for a lasting operation thereon, a hold-down for engaging the bottom of the shoe, means for guiding said hold-down for movement in a predetermined path first from an initial retracted position to a position over the bottom of the shoe and thereafter downwardly into engagement with the shoe, means movable by the operator thus to move the hold-down into position over the bottom of the shoe, and a spring arranged to impart to the hold-down automatically its downward movement into engagement with the shoe upon its arrival in position over the bottom of the shoe, said guiding means being arranged to support the hold-down against downward movement by said spring until it has arrived in that position and for then releasing it to the action of the spring.

4. In a lasting machine, means for supporting a shoe bottom upward for a lasting operation thereon, a hold-down for engaging the bottom of the shoe, means for guiding said hold-down first

for swinging movement widthwise of the shoe from an initial retracted position to a position over the bottom of the shoe and thereafter for rectilinear downward movement into engagement with the shoe, means movable by the operator thus to swing the holddown to its position over the bottom of the shoe, and a spring arranged to impart to the holddown automatically its downward movement upon its arrival in position over the bottom of the shoe.

5. In a lasting machine, means for supporting a shoe bottom upward for a lasting operation thereon, a holddown for engaging the bottom of the shoe, means for guiding said holddown for movement in a predetermined path first from an initial retracted position to a position over the bottom of the shoe and thereafter downwardly into engagement with the shoe, said guiding means being provided with a slot having different portions arranged in divergent relation to each other to guide the holddown respectively in its movement into position over the shoe and in its movement downwardly into engagement with the shoe, the holddown being movable by the operator to the position over the shoe, and a spring arranged to impart to the holddown automatically its downward movement into engagement with the shoe upon its arrival in position over the shoe.

6. In a lasting machine, means for supporting a shoe bottom upward for a lasting operation thereon, a holddown for engaging the bottom of the shoe, a support for said holddown movable to carry it from an initial retracted position into shoe-engaging position, guiding means for said support provided with a slot having different portions arranged in divergent relation to each other, a member carried by said support and movable along said slot, one portion of the slot being arranged to guide the holddown for movement from its initial retracted position to a position over the bottom of the shoe and the other portion of the slot being arranged to guide it for downward movement thereafter into engagement with the shoe, means for moving said holddown support to carry the holddown thus into position over the shoe, and a spring arranged to act on said support to move the holddown automatically downward into engagement with the shoe upon arrival of said member at the junction of the different portions of the slot.

7. In a lasting machine, means for supporting a shoe bottom upward for a lasting operation thereon, a holddown for engaging the bottom of the shoe, means for guiding said holddown for movement from an initial retracted position to a position over the bottom of the shoe and thereafter for downward movement into engagement with the shoe, means for moving the holddown reversely upward to withdraw it from the shoe, and a spring arranged to be subjected to stress by such upward movement of the holddown and to impart thereto automatically reverse movement to its initial position in the path determined by said guiding means upon its arrival at the end of its upward movement.

8. In a lasting machine, means for supporting a shoe bottom upward for a lasting operation thereon, a holddown for engaging the bottom of the shoe, means provided with a slot having an inclined portion for guiding said holddown first for swinging movement widthwise of the shoe from an initial retracted position to a position over the bottom of the shoe and another portion arranged to guide it thereafter for downward

movement into engagement with the shoe, means for moving the holddown reversely upward to withdraw it from the shoe, and a spring arranged to be subjected to stress by such upward movement of the holddown and to impart thereto automatically reverse swinging movement in the path determined by the inclined portion of said slot upon its arrival at the end of its upward movement.

10. 9. In a lasting machine, means for supporting a shoe bottom upward for a lasting operation thereon, a holddown for engaging the bottom of the shoe, means for guiding said holddown for movement in a predetermined path first from an initial retracted position to a position over the bottom of the shoe and thereafter downwardly into engagement with the shoe, a spring arranged to impart to the holddown automatically its downward movement into engagement with the shoe upon its arrival in position over the bottom of the shoe, and means for moving the holddown upwardly to withdraw it from the shoe, said spring being further arranged to return the holddown automatically to its initial retracted position in the path determined by said guiding means upon its arrival at the end of its upward movement.

10. In a lasting machine, means for supporting a shoe bottom upward for a lasting operation thereon, a holddown for engaging the bottom of the shoe, means provided with a slot having an inclined portion for guiding said holddown first for swinging movement widthwise of the shoe from an initial retracted position to a position over the bottom of the shoe and another portion arranged to guide it thereafter for downward movement into engagement with the shoe, a spring arranged to impart to the holddown automatically its downward movement upon its arrival in position over the bottom of the shoe, and means for moving the holddown upwardly to withdraw it from the shoe, said spring being further arranged to swing the holddown automatically to its initial retracted position in the path determined by the inclined portion of said slot upon its arrival at the end of its upward movement.

11. In a lasting machine, means for supporting bottom upward a last and shoe including an insole loose on the last, a holddown mounted for movement from an initial retracted position into position to engage the insole and to hold it in proper relation to the last, a member arranged to be engaged and moved by one of the operator's arms while he is holding the insole properly positioned on the last with both hands, means for imparting to the holddown a portion of its movement toward insole-engaging position by the movement of said member, and a spring arranged to complete automatically the movement of the holddown to insole-engaging position upon its arrival in the position to which it is moved by said member.

12. In a lasting machine, means for supporting bottom upward a last and shoe including an insole loose on the last, a holddown for engaging the insole and holding it in proper relation to the last, said holddown being mounted for movement from an initial retracted position to a position over the bottom of the shoe and for movement thereafter downwardly into engagement with the insole, a member arranged to be engaged and moved by one of the operator's arms while he is holding the insole properly positioned on the last with both hands, means for moving the holddown from its initial position into posi-

tion over the bottom of the shoe by the movement of said member, and a spring arranged to move the holddown automatically downward into engagement with the insole upon its arrival in position over the bottom of the shoe.

13. In a lasting machine, means for supporting bottom upward a last and shoe including an insole loose on the last, a holddown for engaging the insole and holding it in proper relation to the last, means for guiding said holddown first for swinging movement widthwise of the shoe from an initial retracted position to a position over the bottom of the shoe and thereafter for downward movement into engagement with the insole, a member arranged to be engaged and

10

5 moved by one of the operator's arms while he is holding the insole properly positioned on the last with both hands, means for imparting to the holddown its swinging movement into position over the shoe by the movement of said member, and a spring arranged to impart to the holddown automatically its downward movement into engagement with the insole upon its arrival in position over the bottom of the shoe.
